UNITED STATES PATENT OFFICE

154,002

DESIGN FOR A FORK OR SIMILAR ARTICLE

Franz Wagner, Chicago, Ill., assignor to Ekco Products Company, Chicago, Ill., a corporation of Illinois

Application July 17, 1948, Serial No. 147,649

Term of patent 14 years

(Cl. D54—12)

To all whom it may concern:

Be it known that I, Franz Wagner, a citizen of the United States, residing at Chicago, county of Cook, State of Illinois, have invented a new, original, and ornamental Design for a Fork or Similar Article, of which the following is a specification, reference being had to the accompanying drawing, forming part thereof.

Fig. 1 is a front face view of a fork, showing my new design.

Fig. 2 is a side view thereof.

Figs. 3, 4, 5 and 6 represent enlarged sectional views taken on line 3—3, line 4—4, line 5—5 and line 6—6, respectively of Fig. 1.

The dominant feature of the design resides in the portion shown in full lines.

I claim:

The ornamental design for a fork or similar article, as shown and described.

FRANZ WAGNER.
